W. B. Jaynes,

his Attorney.

UNITED STATES PATENT OFFICE.

PAUL H. BENNETT, OF PARIS, TEXAS.

CHECK-BOOK.

1,190,503.

Specification of Letters Patent.

Patented July 11, 1916.

Application filed January 20, 1916. Serial No. 73,158.

To all whom it may concern:

Be it known that I, PAUL H. BENNETT, a citizen of the United States, residing at Paris, in the county of Lamar and State of 5 Texas, have invented certain new and useful Improvements in Check-Books, of which the following is a specification.

This invention relates to improvements in check books, and more particularly to a 10 book of this character adapted to be assembled or bound by unskilled labor. The various parts of the book, including the checks, can be furnished to a bank or like institution. The bank can have the name of 15 a customer printed on the proper number of checks, and the bank can then bind said checks or assemble them within the binder, and turn the same over to the customer. When the checks have been detached, 20 the stubs remain within the binder and the device then forms a convenient receipt book.

The invention consists especially in the manner of constructing the binder for the checks, and of attaching said binder to the 25 usual press board outer covers, or backs, and for holding the same against accidental detachment.

The invention also consists in the novel 30 features of construction hereinafter described, pointed out in the claims and shown in the accompanying drawings, in which:

Figure 1 is a perspective view, the back or cover being raised, and partly broken away. Fig. 2 is a longitudinal section 35 through the book. Fig. 3 is a perspective view of the binder for the stubs. Fig. 4 is a perspective view of the check book backs or covers, in open position, with pivoted clamping devices attached.

In the drawings 1 designates the upper 40 lid and 2 the bottom lid of a check book cover of the usual kind, and of any desired material or construction. The lining 3 on the inner face of the lid 2 is secured along 45 three edges only being open along the edge 4. This lining therefore forms a pocket the use of which will be explained hereafter. Suitable clamping devices 5 are pivoted to the lid 2, adjacent the back of the book, and 50 these members are in the form of flat plates

having corner flanges 5^a, and form binder receiving sockets as will be hereafter explained.

The checks are secured within a suitable case, or holder connected to the stubs and 55 which after the checks have been detached forms a permanent binder for said stubs and makes it very convenient to file them away for future reference. This consists of a folding binder 6 adapted to cover both one 60 edge and both bottom and top of the stubs when checks are detached. The stubs with checks attached are bound in the binder 6, which is suitably reinforced, by eyelets 8, and on the back of the stubs and resting 65 on the outer face of the binder 6, is a tongue 7 of comparatively stiff material. This tongue is separate from the cover 6 and when the parts are to be assembled is slipped into the pocket formed by the lining 3. The 70 tongue is also secured in place by the eyelets 8 as clearly shown.

After the checks and stubs have been placed in the lids 1 and 2 and the tongue 7 inserted in the pocket, the clamps 5 are 75 turned to lie longitudinally with respect to the lids and form retaining sockets for the corners of the stubs, preventing removal of the tongue from the pocket, until the clamps have been moved into an open position. 80 When the stubs are to be put away the binder 6 folds over onto the upper face of the top stub, so that said binder forms a casing for the stubs. A new set of checks and a new binder can then be inserted in 85 place between the lids 1 and 2.

What I claim is:

1. The combination with cover lids one of which has a pocket formed in its inner face, of a binder receiving stubs of checks, and a 90 tongue of comparatively stiff material secured to the back of said binder and entering said pocket.

2. The combination with rigid cover lids, one of which has on its inner face a pocket, 95 of a binder secured to the stubs of checks and adapted to fold over the same when the checks are detached and a stiff tongue secured to the back of said binder and entering the pocket, and fastening means se- 100

curing the binder to the stubs and the tongue to the binder.

3. In a check book cover, lids united by a flexible back, pivoted sockets carried by one of said lids, a pocket being formed in the same lid, a binder for check stubs, and a tongue secured to said binder and entering

the pocket, the corners of the stubs resting in said sockets when said tongue has been inserted in the pocket, as and for the purpose set forth.

In testimony whereof I affix my signature.

PAUL H. BENNETT.
